MULTIPLE RECORD PHONOGRAPH

Joseph Erwood and Harold Holter, Chicago, Ill., assignor, by mesne assignments, to J. P. Seeburg Corporation, Chicago, Ill., a corporation of Illinois

Application April 10, 1939, Serial No. 266,958

5 Claims. (Cl. 274—10)

This invention is directed to that class of phonographs designed for the successive playing of a stack of records, which makes provision for suspending the stack in position above the turntable and in releasing the lowermost record at the proper time to descend to the turntable in preparation for the playing of the record.

The present invention is particularly concerned with special means for supporting the stack of records and for making provision against inequalities in the thickness of the records, or irregularities due to warping or the like.

Further objects and details will appear from the description of the invention in conjunction with the accompanying drawings, wherein,

Figure 1 is a perspective view of the phonograph showing the tone arm swung to its outermost position;

Fig. 2 is a plan view showing the position of the parts at the instant of dropping the record;

Figs. 3 and 4 are details of the releasing mechanism for the records in varying positions of adjustment;

Fig. 5 is a side elevation of the releasing mechanism and support therefor;

Figs. 6 and 7 are details illustrating the automatic adjustment of the arresting blade to arrest a stack including warped records or records of varying thickness;

Fig. 8 is a plan view of the arresting blade;

Fig. 9 is a sectional elevation of the mechanism illustrated in Fig. 5;

Fig. 10 is an inverted plan view looking upwardly from beneath the turntable, showing in particular the cam and connections for actuating the record releasing mechanism, and also showing in part the means for swinging the tone arm;

Fig. 11 is a detail showing the means provided for adjusting the swing of the tone arm either for ten inch or twelve inch records;

Figs. 12, 13 and 14 are details of the cam and associated parts for controlling the swing of the tone arm and also illustrating a portion of the mechanism for releasing the records, the same being shown at different stages in the operation;

Figs. 15 and 16 are details taken on lines 15 and 16 of Figs. 12 and 13, showing the means provided for engaging the record releasing mechanism with the cam for effecting such release;

Figs. 17 and 18 are sectional elevations of the tone arm and the means for lifting and swinging the same;

Fig. 19 is a perspective view of the saddle and associated parts for swinging the tone arm;

Figs. 20 and 21 are sectional details taken on line 20 of Fig. 13, showing the means for releasing the tone arm after needle engagement with the rim of a record;

Fig. 22 is a sectional detail showing the buttons and associated mechanism provided for adjusting the machine to ten inch or twelve inch records, and for manually disabling the automatic operation or releasing records which it is not desired to play; and

Figs. 23, 24, 25 and 26 are details of the tone arm socket and needle inserting means.

The phonograph as a whole is mounted within a box 30 which provides a housing for the operating mechanism, and above the box is located a turntable 31 and a tone arm 32. The stack of records to be played is suspended in position above the turntable and the records are mounted upon a centrally disposed spindle 33 so that each record when released will slide down into properly centered position upon the turntable or upon previously deposited records carried by the turntable. Thus, as the records are successively deposited, the stack above will be depleted and the stack upon the turntable will be augmented, and in view of this circumstance the lift of the tone arm must be sufficient to clear the maximum height of the complete stack when deposited upon the turntable.

30 Record supporting mechanism

The release of the lowermost record is effected in each instance by the oscillation of a supporting blade 34 which when swung as in Fig. 3 will underlie the lowermost record of the stack. The action of the supporting blade is supplemented by the action of a separating blade 35 which is mounted slightly above the supporting blade and in position to swing inwardly between the lowermost record and the one immediately above in order to retain the remainder of the stack when the lowermost record is released. The blade 35 is provided with a knife edge 36 to afford easy entrance between the records, and both of the blades are supported in the manner best illustrated in Figs. 5 to 9 inclusive.

It will be understood that the releasing mechanism herein described is in effect a record escapement and is duplicated at diametrically opposite sides of the turntable, but the description of one of these escapements will suffice for both.

The supporting blade 34 is rigidly secured to a tubular head 37 which is carried at the upper end

of an oscillating shaft 38 provided with a groove 39 which receives the inner end of a screw 40 which serves to hold the parts in assembled relation, but in order to properly adjust the releasing assembly for either ten or twelve inch records, the tubular head 37 at its lower end is provided with cross grooves 41, 41, either of which may be adjusted to engage a cross pin 42 extending through the oscillating shaft 38. Furthermore, the acting knife edge 36 of the separating blade is rounded to afford an inner hump 43 which engages between twelve inch records, and an outer hump 44 configured to engage between ten inch records, the latter having a more extended inward swing than the former, as will be apparent from Fig. 3, which illustrates a twelve inch record in full lines and a ten inch record in a dot and dash line.

The separating blade 35 is carried by a hub 45 which is journalled upon a post 46 upwardly extending from the tubular head 37, and shouldered at 47 to receive the thrust of a spring 48, the upper end of which bears against a disk 49 mounted upon the post and above the upper terminus of the hub. These parts are enclosed by a cap 50 carried by the hub 45. The lower face of the hub is provided with depending wedge shaped lugs 51 separated by recesses 52 which coact with one or more bosses 53 formed on the upper surface of the tubular head 37, the arrangement being such that, in the event the knife edge of the separating blade engages the edge of a record during the inward swing of the blade rather than the gap between adjacent records, the separating blade is held stationary while the tubular head 37 of the supporting blade 34 continues to rotate. The bosses 53 moving relatively, the inclined surfaces of the lugs 51 cam up the separating blade 35 (Figs. 6 and 7) sufficiently to clear the edge of the lowermost record and slip into the stack above the lowermost record in order to retain the remainder of the stack while the lowermost record is being dropped. The separating blade being subject to the thrust of the spring 48 will thus yield sufficiently to accommodate the condition mentioned.

However, it is essential to allow only a limited independent rotation between the supporting blade and the separating blade, and to meet this requirement the inner end of the supporting blade is provided with an arcuate groove 54 (Fig. 8) which terminates in slots 55 and 56, the former of which establishes the proper correlation between the blades for ten inch records, while the latter is adapted for twelve inch records.

The inner end of the separating blade is provided with a pin 57 which when the blade is lowered will enter either the slot 55 or the slot 56 as the case may be, so that the rotative freedom of the separating blade will be limited by the length of the slot, it being understood, however, that by manual adjustment the pin 57 can be elevated sufficiently to swing through the groove 54 in order to set the separating blade at the proper angle for records of the intended size. The slots 55 and 56 are made long enough, however, to allow sufficient rotation to give to the separating blade the required lift to find entrance between records of unusual thickness or irregular edge contour. A finger 58 struck upwardly from the inner edge 59 of the supporting blade 34 cooperates with indicia on the arcuate inner edge 60 of the separating to indicate the size of the record for which the blade 35 is set. The blade 35 is recessed at 61 to admit the finger 58.

Tone arm mechanism

The tone arm 32, as shown, is of channeled elbow shape comprising an outer horizontal arm section 62 and a vertical mounting section 63. At the bend of the elbow the tone arm is pivoted upon a cross pintle 64 carried by the head 65 of a tone arm shaft 66, which extends through a journal sleeve 67 rigidly mounted upon a boss 68 formed on the upper surface of the top plate 69 of the box 30. The journal sleeve is provided with a threaded extension 70 which receives nuts 71 for rigidly holding the sleeve in position, and below said extension the tone arm shaft is entered freely through a collar 72 provided on each side with trunnion mountings 73 upon which the wings 74 of a saddle 75 are mounted, thus permitting the saddle to have a limited tilting movement, which is necessary in the lifting of the tone arm and the engagement of the parts with the cam for swinging the tone arm across the face of the turntable.

The saddle comprises a body portion 76 from which the wings extend laterally, which body portion is provided with an inwardly extending arm 77 having on its end a depending cam roller 78 which is adapted, when the saddle is tilted, to engage with a cam groove 79 in the upper surface of a constantly rotating main gear 80. The cam groove comprises a circumferentially extending portion 81 which merges at one end into an inwardly extending portion 82 terminating in an enlarged recess 83 in the face of the main gear. The opposite end of the groove portion 81 is flared at its point of entrance 84 into the recess, and the inner wall 85 of the groove is rounded and extends inwardly in a radial direction, the arrangement being one which serves to guide the cam roller 78 when depressed into the recess 83 until it enters the throated mouth 84 of the circumferentially extending portion 81 of the cam groove.

The saddle below the arm 77 is provided with a pair of spaced ears 86 between which is pivoted a bell crank member 87 mounted upon a pintle 88 and carrying a roller 89 at its lower end. The upper end of the bell crank member has pivoted thereto a tubular member 90 provided on its interior with a spring 91 which bears against the head 92 of a thrust rod 93 which acts against a bridge plate 94 on the under side of the tone arm, and the upper end of the thrust rod is guided through an aperture 95 at the outer end of an arm 96 terminating in a collar 97 rigidly secured to the tone arm shaft 66.

The tone arm shaft has rigidly affixed thereto near its lower end a plate 98 provided with an arm 99 terminating in an upturned finger 100 which lies between ears 101, 101 formed on superposed disks 102 loosely mounted upon the tone arm shaft. Between the ears 101 is located a downturned finger 103 formed at the outer end of a base plate 104 which is rigid with the base of the collar 72. Each of the superposed disks 102 is provided on its outer edge with an upturned ear 105, which ears are cross connected by a spring 106, and in addition the ear 105 on the uppermost disk has also connected thereto an obliquely upwardly extending spring 107 (Fig. 18) connected at its upper end to the top plate 69 of the phonograph box. A spring 108 connects the plate 104 with an ear 109 on one end of the wings of the saddle, which normally imparts an uptilting movement to the arm 77.

The arrangement of these parts is such as to

interpose a yielding connection in either direction between the collar 72, which when the parts are operating is in unyielding engagement with the groove 81, and the tone arm shaft, so that the latter may yield under spring tension if subjected to manual or accidental pressure without tending to jamb or injure the operating mechanism. Likewise, the tone arm will be yieldingly supported by the thrust rod 93.

The base plate 104 has inwardly projecting therefrom an arm 110 provided at its end with an ear 111 through which is entered a trip contact screw 112 (Figs. 12, 13 and 14). When the tone arm is swung inwardly during its terminal movement the trip contact is brought into engagement with a finger 113 connected with a bell crank latch 114 having a hooked finger 115 which is adapted to engage with a notched lug 116 on the upper face of a control bar 117 pivoted on a pintle 118 entered through a lower frame plate 119 which lies below the plate 69, being connected therewith at intervals by the provision of hanger flanges 120.

The pivoted control bar at its outer end is provided with an arcuate cam head 121 the edge of which is adapted to engage the roller 89 to impart the required tilting movements to the saddle and associated parts. The control bar lies below the plane of the main cam gear 80, which in Figs. 12, 13 and 14 has been partially broken away to reveal the underlying mechanism. The control bar when released is drawn back by a coil spring 122 having its end secured to a fixed bracket 123 on the plate 119. The control bar carries a trip finger 124 secured thereto by a pivot 125, and normally thrown back as in Fig. 13 by the pull of a spring 126 having its end secured to the control bar.

The trip finger 124 is wedge shaped at its outer end 127 and rides upon the surface of a control cam 128 mounted upon a shaft 129 which also carries the main gear. The control cam throughout its major extent is circular, and on one side is provided with a depression 130 terminating in an abrupt shoulder 131.

The configuration of the control cam in relation to the trip finger 124 is such that when the control bar is unlatched and drawn to the right by the pull of the spring 122, the free end of the trip finger will lie in the path of the abrupt shoulder 131 of the cam, so that when the parts are engaged the finger will be projected and caused to ride upon the circular portion of the control cam as in Fig. 12, which relationship of the parts will continue until the depression 130 in the cam is reached, prior to which time the control bar will be swung to the left, which causes its arcuate head to engage with the saddle roller 89, imparting a tilting movement to the saddle during the interval while the tone arm is elevated and swinging from its innermost to its outermost position, and thence back to its starting point near the rim of the record. It is this tilting movement of the saddle which imparts an upward lift to the thrust rod 93 and a downtilting of the arm 77 which brings the roller (or pin) 78 into engaging relation with the depression and cam groove on the upper surface of the main gear.

When the depression 130 in the control cam reaches the trip finger 124, the latter will be released and drawn back into the oblique position shown in Fig. 13 which will allow the latch hook 115 to hold the control bar in the position shown in that figure, which releases the saddle roller 89 from contact with the cam head of the control bar and breaks connection between the roller 78 and the cam groove on the main gear, so that with the operating train thus broken the tone arm is free to travel inwardly with the needle upon the record line while the driving mechanism runs idly until the parts are reengaged at the inward terminus of the movement.

In order to properly regulate the dropping of the tone arm to the rim of either a ten inch or a twelve inch record as the case may be, a draw bar 132 is employed, which is provided near its end with a notch 133 positioned to engage with a stop finger 134 on the outer margin of the plate 98 which is fast with the tone arm shaft 66. The draw bar is provided with extension bars 135 and 136 connected thereto by screws 137 entered through slots 138 which permit adjustment of the extensions by means of a screw 139 having an inturned end 140 connected with the bar 132, and having its free end entered through downturned ears 141 and 142 depending from the extension bars 135 and 136. Nuts 143 are provided for holding the parts in adjusted relation. The draw bar also carries an abutment block 144 which is secured by the screws 137 and is adapted to be engaged by an obliquely disposed pivoted thrust finger 145.

The extension bar 136 is provided near its outer end with a slot 146 adapted to receive the lower end of a thrust rod 147 provided with a button 148 which adjusts the draw bar for ten inch records. A similar thrust rod 149 provided with a button 150 adjusts the draw bar for twelve inch records.

The thrust rods are guided through the top plate 69 of the phonograph box and through a hanger plate 151 secured below the plate by brackets 152. Similarly mounted thrust rods 153 and 154 having buttons 155 and 156 are provided, the first of which is adapted to disable the automatic operation of the machine to permit records to be manually employed in the conventional manner, and the second of which is provided for manually releasing a record at any time irrespective of the timing of the automatic release. Each of the thrust rods is provided with an elongated slot 157 through which extends a restoring bar 158 provided with bevel edged prongs 159 adapted, in the case of the thrust rods 147, 149 and 153, to be engaged by the upper terminus of the associated slot 157, so that as a button is depressed the restoring bar will be moved to the right until the thrust rod is depressed sufficiently to permit the associated prong to spring into an upper slot 160. In the case of the thrust rod 154, however, the upper slot 160 is omitted.

Each of the thrust rods operates against the tension of a coil spring 161, and the restoring bar at its left hand end is provided with a disk 162 bearing against an interposed spring 163 which tends to move the restoring bar to the left when released. The arrangement is such that the depression of any one of the three buttons 148, 150, 155 will cause the upper end of the slot 157 to cam against the associated prong 159, moving the restoring bar to the right until the thrust rod has been depressed sufficiently to permit the prong to snap into the upper slot 160 which holds the button depressed until another button of the series is depressed, which releases the first button and holds the second button in depressed position. The slot 157 in the thrust rod 154 is, however, ineffective to operate the restoring bar, so that the button 156 will remain depressed only while sub-

jected to manual pressure. The right hand end of the restoring bar is entered through a slot 164 in the obliquely disposed thrust finger 145 which at its upper end is provided with an offset tongue 165 entered through a slot 166 which pivots the thrust finger at its upper end. The arrangement of these parts is such that the depression of the button 158 will cause the end of the thrust rod 147 to enter the slot 146 in the extension bar 136 which adjusts the thrust bar 132 for ten inch records.

The depression of the button 158 will first cause a movement of the restoring bar 158 to the right, which swings the pivoted thrust finger 145 to the right, thereby moving the thrust bar assembly sufficiently to permit the end of the thrust rod 149 to clear the rear end of the extension bar 136, which holds the parts in position for twelve inch records. In either adjustment, the tone arm will swing inwardly until the stop finger 134 engages the notch 133, which is adjusted to the correct position for either ten inch or twelve inch records.

Record releasing mechanism

The record releasing mechanism is controlled by a cam groove 167 on the lower face of the main gear 80 (Figs. 10, 15 and 16). This groove coacts with a roller 168 carried by an arm 169 pivoted at its outer end to a pivot 170 carried by the lower frame plate 119.

The arm 169 is provided with a lower offset 171 and an upper offset 172, and the lower offset is configured to allow the control bar 117 to cam under the offset 171 which lifts the arm 169 as in Fig. 16, which thus throws up the roller 168 into engagement with the cam groove 167. The in-thrown of the control bar is resisted by the spring 122. The free end of the arm 169 has pivoted thereto a link 174 which at its outer end is pivoted to a crank finger 175 which is freely mounted upon the hub 176 of a companion crank finger 177 secured by a set screw 178 to one of the record releasing shafts 38.

The two crank fingers are connected by a coil spring 179 which is carried around a grooved drum 180 journalled upon the lower end of the hub 176. The crank finger 177 is connected by a link 181 with a crank finger 182 on the companion record releasing shaft 38. This arrangement interposes a yielding spring connection between the cam controlled connections and the shafts 38, which is desirable to prevent any breakage in the event the releasing blades become jammed or are accidentally subjected to blows or pressures.

In order to release the tone arm for inward travel along a record line immediately after the deposit of a record, a trip bar 183 (Fig. 10) is pivoted to the notched end of the thrust bar 132, and the free end of the trip bar is provided with an upstanding hooked finger 184 extending through a slot 185 in the lower frame plate (Fig. 20), which finger is adapted to be engaged at the proper instant by the edge of the arm 169, the parts being so related that at the terminus of the movement of the arm it will move the trip bar 183 and release the notch 133 from engagement with the stop finger 134, thereby allowing the tone arm to swing freely in its inward movement across the surface of the record.

The phonograph is driven by a motor 186 operating through reduction gearing 187 to drive 70 the turntable shaft 188 which is in train through gearing 189 with the main cam gear 80, so that during the normal operation of the machine the turntable and main gear will be constantly driven at properly related speeds.

Manual record release

The means for manually releasing the records by the depression of the button 156 will now be described: The lower end of the thrust rod 153 is positioned to engage a crank finger 190 (Fig. 10) on the end of a rocking rod 191, which at its opposite end is provided with an upturned finger 192 (Fig. 20), which finger when rocked will engage the tail end of the finger 113 (Fig. 12) and release the latch 114, so that by the depression of the button at any time the control bar may be thrown into action to entrain the cams with the associated mechanisms and lift and restore the tone arm to its outermost position and release a new record without waiting for the normal automatic operation to occur.

Disabling mechanism

Where it is desired to disable the automatic 20 operation of the machine, the button 155 is depressed, thereby causing the thrust rod 153 to engage a crank finger 193 on the end of a rocking rod 194, which carries at its opposite end a finger 195 adapted to be turned upwardly into position 25 to engage the cam head 121 of the control bar 117, which prevents the inward movement of the control bar necessary to engage the trip finger 124 with the cam shoulder 131, so that automatic operation of the machine will be disabled and the 30 machine may be employed as a manually operated machine in the usual manner so long as the button remains depressed.

Tone arm cradle

35 In Figs. 23, 24, 25 and 26 is illustrated a tone arm cradle 196 for supporting the free end of the tone arm when in its outermost position. This cradle is of channel shaped formation provided with an outer high wall 197 and an inner low wall 198 connected by a base plate 199 which supports a needle socket 200 provided with an aperture 201 for the reception of the point of a needle 202, the socket being obliquely supported upon a plate 203, the outer end of which is slightly elevated 40 to afford the desired obliquity.

The plate 203 is provided in its center with a headed stud 204 surrounded by the convolutions of a spring 205, the ends of which are entered through apertures 206 in the inner and outer walls of the cradle, which affords a yieldable mounting for the plate 203, so that it may adapt itself to the pressure of the needle, and as the same is swung down into the socket aperture, the butt end of the needle is socketed within a block 207 in the head of the tone arm and held rigidly by a thumb screw 208. This arrangement not only provides a suitable rest or support for the tone arm but serves to protect the point of the needle, and at the same time affords a convenient means for the insertion of a needle which may be positioned point downwardly within the socket aperture, so that when the tone arm is brought into register with the butt end of the needle it may be easily inserted into position and locked by the set screw.

Operation

In operation, with the stack of records held in elevated position upon the supporting blades, and with the machine in operation, the lowermost record may be automatically dropped by the depression of the button 156, which releases the latch 114, allowing the control bar to swing inwardly to bring the trip finger 124 into position 75 to be engaged by the cam shoulder 131. As the

cam rotates, the control bar will be swung outwardly and into position to tilt the saddle in the manner previously described, which has the effect of elevating the tone arm and simultaneously engaging the roller 78 with the cam groove on the upper surface of the main gear.

With the parts thus engaged, the roller 78 will move outwardly, thereby imparting an outward swing to the tone arm until the circumferential groove portion 81 of the cam is encountered, which will hold the tone arm in its outermost position during the release of the first record, which is effected by the engagement of the roller 168 with the cam groove on the under surface of the main gear. This imparts the necessary 15 rocking movements to the supporting blades to release the first record and simultaneously arrest the descent of the remainder of the stack by the engagement of the arresting blades.

At the conclusion of the record releasing operation, the arresting blades will move outwardly allowing the stack to fall slightly behind the releasing blades, where the stack will be held during the playing of the first record. As the needle approaches its innermost position, at the terminus of the record line, it will encounter a steeply pitched inner groove in the record and be drawn inwardly to its final position, which terminal movement brings the contact screw 112 into engagement with the finger 113 of the latch 114, thereby automatically releasing the control bar and initiating the second cycle of operations of the character first described. Thereafter, unless it is desired to manually drop one or more records, the automatic operation will continue uninterruptedly throughout the entire series and in properly timed relation.

The arcuate configuration of the cam head 121 of the control bar is such as to afford a circular path of travel for the saddle roller 89, so that, throughout the outward swing of the tone arm and thereafter during its short inward swing to record engaging position, the operating parts will be held in engagement with the respective cams, but this cam engagement will be terminated at the instant the trip finger 124 encounters the depression in the cam 128, so that at this instant the control arm will swing backwardly to the latched position illustrated in Fig. 13, which releases the saddle and disengages the cam actuated train of connections.

The lift of the tone arm must, of course, be sufficient to clear the uppermost record of a stack when all are deposited upon the turntable, but the weight of the tone arm will act against the tension of the spring 91, so that in overcoming said spring tension, the descent of the tone arm will be cushioned to the desired extent so that easy contact of the needle with the record groove will be effected.

The mechanism as a whole is of comparatively simple construction, in that the operations required, both in lifting and moving the tone arm, as well as the operations required in releasing the records from the elevated stack, are all controlled by cams mounted upon opposite sides of the main gear, the shaft of which also provides a mounting for the cam 128, which regulates the timing of the control bar, and which in turn times and regulates the lifting of the tone arm.

This simplification of the structure enables the number of operating parts to be reduced to a minimum and affords ruggedness and precision of operation without the need for providing involved methods of power transmission in afford-

ing the necessary movements in properly timed relation.

Although the invention has been described with particularity as to detail, it is not the intention to limit the invention solely to the form shown, since modifications may be made therein without departing from the spirit of the invention.

We claim:

1. In a multiple record phonograph including a turntable and a tone arm in coacting relation therewith, means for holding a stack of phonograph records in elevated relation above the turntable, said means comprising a plurality of rotatable upright mountings each carrying a record releasing device including a supporting blade configured to normally underlie and support a stack of records and when rotated to remove the support thus afforded, and a separating blade in superposed relation to the supporting blade and configured to normally clear the stack of records and when rotated to enter between the lowermost record of the stack and the next succeeding record, the blades having limited relative vertical and rotative movement with respect to one another, and cam elements interposed between said blades and movable with said blades and adapted when said blades are subjected to relative rotation to elevate the separating blade with respect to the supporting blade to accommodate records of varying thickness, the blades being rotatable in unison to release the lowermost record and retain the remaining records in the stack.
2. In a multiple record phonograph including a turntable and a tone arm in coacting relation therewith, means for holding a stack of phonograph records in elevated relation above the turntable, said means comprising a plurality of rotatable upright mountings each carrying a record releasing device including a supporting blade configured to normally underlie and support a stack of records and when rotated to remove the support thus afforded, and a separating blade in superposed relation to the supporting blade and configured to normally clear the stack of records and when rotated to enter between the lowermost record of the stack and the next succeeding record, the blades having limited relative vertical and rotative movement with respect to one another, and cam elements interposed between said blades and movable with said blades and adapted when said blades are subjected to relative rotation to elevate the separating blade with respect to the supporting blade to accommodate records of varying thickness, the blades being rotatable in unison to release the lowermost record and retain the remaining records in the stack, and means for adjustably locating the separating blade with respect to the supporting blade to accommodate records of different sizes.
3. An escapement mechanism for automatic phonographs comprising an upper and a lower supporting member, means connecting said members together for simultaneous and relative movements, the upper member being adapted to enter a stack of records supported on the lower member and above the lowermost record, and registering overlying cam means on the adjacent faces of said members, one of said cam means having an inclined plane surface whereby relative movement between the members resulting from arrestment of the upper member by engagement with the lowermost record causes the cam means to elevate the upper member into position for entry 75 into the stack above the lowermost record.

4. An escapement mechanism for automatic phonographs comprising an upper and a lower supporting member, means connecting said members together for simultaneous and relative movements, means limiting the relative movement between the members, the upper member being adapted to enter a stack of records supported on the lower member and above the lowermost record, and registering overlying cam means on the adjacent faces of said members, one of said cam means having an inclined plane surface whereby relative movement between the members resulting from arrestment of the upper member by engagement with the lowermost record causes the cam means to elevate the upper member into position for entry into the stack above the lowermost record.

5. An escapement mechanism for automatic phonographs comprising an upper and a lower supporting member, means connecting said mem-

bers together for simultaneous and relative movements, means limiting the relative movement between the members, the upper member being adapted to enter a stack of records supported on the lower member and above the lowermost record, registering overlying cam means on the adjacent faces of said members, one of said cam means having an inclined plane surface whereby relative movement between the members resulting from arrestment of the upper member by engagement with the lowermost record causes the cam means to elevate the upper member into position for entry into the stack above the lowermost record.
